(57) **CLAIM**

The ornamental design for a vertically-oriented transaction device, as shown and described.

DESCRIPTION

FIG. 1 is a front perspective view of a first embodiment of the vertically-oriented transaction device showing our new design;

FIG. 2 is a front elevational view thereof;

FIG. 3 is a back elevational view thereof;

FIG. 4 is a side elevational view thereof;

FIG. 5 is an opposite side view thereof;

FIG. 6 is a bottom plan view thereof;

FIG. 7 is a top plan view thereof;

FIG. 8 is a front perspective view of a second embodiment of the vertically-oriented transaction device;

FIG. 9 is a front elevational view thereof;

FIG. 10 is a back elevational view thereof;

FIG. 11 is a side elevational view thereof;

FIG. 12 is an opposite side elevational view thereof;

FIG. 13 is a bottom plan view thereof;

FIG. 14 is a top plan view thereof;

FIG. 15 is a front perspective view of a third embodiment of the vertically-oriented transaction device;

FIG. 16 is a front elevational view thereof;

FIG. 17 is a back elevational view thereof;

FIG. 18 is a side elevational view thereof;

FIG. 19 is an opposite side elevational thereof;

FIG. 20 a bottom plan view thereof; and,

FIG. 21 is a top plan view thereof.

The shading in the drawings is provided to illustrate surface color variations of the design and it is not intended to be illustrative of texture.

The broken lines in the drawings illustrate environmental structure on the article and form no part of the claimed design.
